No. 755,454.

PATENTED MAR. 22, 1904.

C. CLEAR.
CLINKER TONGS.

APPLICATION FILED NOV. 2, 1903.

NO MODEL.

UNITED STATES PATENT OFFICE.

CHARLES CLEAR, OF ST. LOUIS, MISSOURI.

CLINKER-TONGS.

SPECIFICATION forming part of Letters Patent No. 755,454, dated March 22, 1904.

Application filed November 2, 1903. Serial No. 179,460. (No model.)

To all whom it may concern:

Be it known that I, CHARLES CLEAR, a citizen of the United States, residing in the city of St. Louis, in the State of Missouri, have 5 invented certain new and useful Improvements in Clinker-Tongs, of which the following is a full, clear, and exact description, reference being had to the accompanying drawings, forming part of this specification.

10 My invention relates to a tool for use in removing clinkers from the fire-boxes of furnaces and boilers, the object being to construct a tool for this purpose which will firmly grasp the clinkers, which will be sufficiently 15 long to reach any part of the fire-box, and which while being light will be sufficiently rigid and strong to remove large and heavy cinders.

15 The invention consists in features of novelty hereinafter fully described, and pointed out in the claim.

20 Figure I is a perspective view of my improved tongs. Fig. II is an enlarged detail top view. Fig. III is an enlarged detail section taken on line III III, Fig. I. Fig. IV is 25 a longitudinal section taken on line IV IV, Fig. II. Fig. V is an enlarged transverse section taken on line V V, Fig. IV.

25 Referring to the drawings, 1 represents a handle, the outer end 2 of which is preferably covered with leather or some other material which is a non-conductor of heat. To the forward end of this handle is pivoted at 3 a pair of jaws 4, having inwardly-extending arms 5, 30 through which the rivet 3 passes. The jaws 4 are twisted at 6, so that while the arms 5 lie flat on the handle 1 the wide parts of the jaws stand vertical. Resting upon the handle 1 is 35 a sliding bar 7, connected at its inner end to the arms 5 by means of links 8, loosely riveted to the bar and to the ends of the arms. The bar 7 is loosely connected to the handle 1 by means of rivets 9, fitting in slots 10, formed 40 in the handle, and the outer portion of the 45 bar has a twist 11 that throws its extreme outer end at right angles to the handle, and this end of the bar is covered with leather or

some other non-conductor of heat, thus forming a handle by which the bar can be moved back and forth on the handle, and as it is thus 50 moved the jaws 4 are opened and closed from the position shown in dotted lines, Fig. II, to the position shown in full lines.

In the use of the tongs the inner end of the tool is inserted into the furnace, and by pushing 55 inwardly on the bar 7 the jaws are opened out, and then when the jaws have been adjusted over a cinder an outward pull on the bar will cause them to firmly grasp the cinder, so that it can be drawn from the fire-box 60 by means of the tool.

It is important that the article be light, so that it can be easily handled, and to have it quite long, as is necessary to do the work I form the handle 1 of channel-iron, which combines 65 lightness with strength and rigidity. The bar 7 is secured to the back of the channel-iron, and the lower heads of the rivets 9 being located in the channel of the iron they do not rub or come in contact with the door-frame of the fire-box, so that the tool will work 70 smoothly in being run into and drawn from the fire-box.

I claim as my invention—

In clinker-tongs, the combination of a channel-shaped bar having a handle at its outer end and provided with a longitudinal slot, a sliding bar on the flat side of said channel-bar, a rivet in said sliding bar to slide in the slot in said channel-bar; the rear part of said sliding bar being twisted to form an integral handle extending at a right angle to the bar, a pair of twisted jaws forming forward gripping members, and rearwardly-extending arms at right angles thereto and pivoted to 85 the flat side of said channel-bar, and a pair of connecting-links pivoted to said jaw-arms and to said sliding bar, substantially as and for the purposes set forth.

CHARLES CLEAR.

In presence of—

E. S. KNIGHT,
BLANCHE HOGAN.
